US0D1078410S

(12) **United States Design Patent** (10) Patent No.: **US D1,078,410 S**
(45) Date of Patent: ** Jun. 10, 2025

(54) **BOTTLE RACK**

(71) Applicant: **ZHEJIANG CHENG'S PLASTIC PRODUCTS CO., LTD.**, Zhejiang (CN)

(72) Inventor: **Bo Cheng**, Jiangxi (CN)

(73) Assignee: **ZHEJIANG CHENG'S PLASTIC PRODUCTS CO., LTD.**, Jinhua (CN)

(**) Term: **15 Years**

(21) Appl. No.: **29/979,629**

(22) Filed: **Dec. 19, 2024**

(51) LOC (15) Cl. **07-09**

(52) U.S. Cl.

USPC **D7/701**; D6/672

(57) **CLAIM**

The ornamental design for a bottle rack as shown and described.

DESCRIPTION

FIG. 1 is a perspective view of a bottle rack showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the bottle rack that form no part of the claimed design.

1 Claim, 8 Drawing Sheets
